UNITED STATES PATENT OFFICE.

THOMAS C. JOHNSON, OF NEW HAVEN, CONNECTICUT, ASSIGNOR TO WINCHESTER
REPEATING ARMS CO., OF NEW HAVEN, CONNECTICUT, A CORPORATION.

TRIGGER MECHANISM FOR FIREARMS.

1,297,859.

Specification of Letters Patent. Patented Mar. 18, 1919.

Application filed January 9, 1919. Serial No. 270,384.

To all whom it may concern:

Be it known that I, THOMAS C. JOHNSON, a citizen of the United States, residing at New Haven, in the county of New Haven 5 and State of Connecticut, have invented a new and useful Improvement in Trigger Mechanism for Firearms; and I do hereby declare the following, when taken in connection with the accompanying drawings and 10 the characters of reference marked thereon, to be a full, clear, and exact description of the same, and which said drawings constitute part of this application, and represent, in—

15 Figure 1 a broken view partly in vertical section and partly in side elevation, of a firearm trigger-mechanism constructed in accordance with my invention.

Fig. 2 a view in vertical transverse section 20 on the line 2—2 of Fig. 1.

Fig. 3 an enlarged view in vertical longitudinal section of the trigger.

My invention relates to an improvement in trigger-mechanisms for firearms, the object 25 being to simplify and cheapen the construction of such mechanisms.

With these ends in view, my invention consists in a trigger-mechanism for firearms, having certain details of construction 30 as will be hereinafter described and pointed out in the claims.

In carrying out my invention as herein shown, the trigger 3 is hung upon a pivot 4 passing transversely through the guard 5 35 which is formed with an integral finger-loop 6 inclosing and protecting the said trigger the forward end of which is formed with a sear-nose 7 engaging with sear-notches 8 formed in the rounded lower end of a hammer 9 hung upon a pivot 10 also mounted in the said guard. For normally maintaining the sear-nose 7 in engagement with the hammer, I form the trigger with a cylindrical upwardly opening hole 11 extending 40 down into it from its upper edge at a point directly to the rear of its pivot 4. This hole receives a helical trigger-spring 12 the upper end of which abuts against a transversely arranged stop-pin 13 mounted in the 45 said guard and discharging the two-fold function of holding the spring in place and acting as a stop to limit the upward movement of the rear end of the trigger, which is formed for this purpose with a transversely arranged semi-circular seating-re-

cess 14 intersecting the upper end of the upwardly opening hole 11, the recesses receiving the pin 13 when the same is acting as a stop-pin for the trigger as described. For the reception of the trigger 3 and the lower 60 end of the hammer 9, the guard 5 is formed with an upwardly opening horizontal cut or deep slot 15 which also opens downwardly at 65 16 into the finger-loop 6, the pivots 4 and 10 and the stop-pin 13 extending transversely across this slot. The construction described is not only simple and cheap, but very convenient in the matter of assembly and disassembly.

I claim:—

1. In a firearm, a trigger formed at the rear of its pivot with an upwardly opening hole, a helical trigger-spring located in said hole, and a transversely arranged stop-pin mounted in the arm and extending above the 70 trigger in position to form an abutment for the upper end of the said spring and also acting as a stop to limit the upward motion of the rear end of the trigger.

2. In a firearm, a trigger formed at the 75 rear of its pivot with an upwardly opening hole leading into a semi-circular transverse trigger-stop recess, a helical trigger-spring located in said hole, and a transversely arranged stop-pin mounted in the gun and extending above the trigger in position to form an abutment for the upper end of said spring and to co-act with the said transverse trigger-stop recess to limit the upward movement of the rear end of the trigger. 80

3. In a trigger mechanism for firearms, the combination with a guard having a deep longitudinal slot for the reception of the trigger mechanism, of a hammer entering the said slot and pivotally mounted in the 85 said guard, a pivotally mounted trigger located in the said slot, co-acting directly with the said hammer and formed at a point to the rear of its pivot with an upwardly opening hole, a helical trigger spring located in 90 the said hole, and a transversely arranged stop-pin mounted in the said guard and extended across the slot thereof in position to form an abutment for the upper end of the said spring and to limit the upward movement of the rear end of the trigger. 100

4. In a trigger mechanism for firearms, the combination with a guard having a deep longitudinal slot for the reception of the trigger-mechanism, of a hammer entering the 105

said slot and pivotally mounted in the guard, a pivotally mounted trigger located in the said slot, coacting directly with the said hammer and formed at a point to the rear 5 of its pivot with an upwardly opening hole intersected at its upper end by a transverse recess, a helical trigger spring located in the said hole, and a transversely arranged stop-pin mounted in the gun and extending 10 above the trigger in position to form an abutment for the upper end of said spring

and to co-act with the said recess in the trigger to limit the upward movement of the rear end thereof.

In testimony I have signed this specification in the presence of two subscribing witnesses.

THOMAS C. JOHNSON.
